UNITED STATES PATENT OFFICE.

MUNSON H. TREADWELL, OF NEW YORK, N. Y., AND CARL P. ASTROM, OF EAST ORANGE, NEW JERSEY, ASSIGNEES TO M. H. TREADWELL COMPANY, A CORPORATION OF NEW YORK.

DUMPING-CAR.

No. 902,779.

Specification of Letters Patent.

Patented Nov. 3, 1908.

Application filed March 4, 1908. Serial No. 419,110.

To all whom it may concern:

Be it known that we, MUNSON H. TREADWELL and CARL P. ASTROM, citizens of the United States, residing at New York, in the county of New York and State of New York, and East Orange, county of Essex, and State of New Jersey, respectively, have invented certain new and useful Improvements in Dumping-Cars, of which the following is a full, clear, and exact specification.

This invention relates to dumping cars, and has particular reference to cinder cars or the like wherein a tilting and bodily movable car body is mounted to be dumped in opposite directions from a central upright position, as may be desired.

More particularly, the invention comprises a power actuated dumping car having a single cylinder and piston of a stroke equal to the bodily movement in either direction, the cylinder being bodily movable from one side to the other of the car frame according to the direction in which the car body is to be dumped. By such an arrangement it is possible to provide a cylinder actuated dumping car in which the cylinder will not project outside the permissible distance from the rails, and also a saving in weight and simplification of the mechanism is effected. As herein shown, the car body is supported on trunnions which carry gears engaging fixed racks carried on the car frame, of well known construction, and the piston rod of the cylinder engages one trunnion, to move the car body in one or the other direction from the central position according to the position of the cylinder at one or the other side of the center.

The cylinder is itself mounted to swing vertically on a rack from one to the other side of the car frame when it is desired to dump on a different side, and flexible or adjustable fluid pressure connections are provided for the cylinder in either position.

The invention will be more readily understood in connection with the description of the accompanying drawings, wherein

Figure 1 represents an end view of a dumping car embodying the invention, and Fig. 2 represents a detail plan view of one of the trunnions.

The car frame comprises the usual under frame carried by end bolsters 1, the under frame not being herein shown, and is supported at the ends on trucks which will not be particularly described herein, as these

may be arranged according to particular necessities. The bolsters 1 each have a stationary rack 2 and a track 3, and the car body 4, is preferably secured to a bail 5 which is provided with trunnions 6 at diametrical points. Rigidly secured to the trunnions 6 are gears 7 adapted to mesh with the racks 2 (at each end of the car body) and rollers 8 which roll on the tracks 3, the parts thus far described being of a well known construction. In order to actuate the car body a cylinder 9, having a piston 10 and a piston rod 11 engaging the trunnion 6 is provided, so that when fluid pressure is admitted at one end of the cylinder the piston will be moved to the other end, and thereby the car body moved laterally and simultaneously tilted. In the position shown in the drawings, the car body is in position to be tilted and discharged to the left. It is desirable in cars of this type, that provision be made for dumping the car body at either side, as may be desired, and to this end, the cylinder 9 is movably mounted so that it can be shifted from the right side as shown in the drawings, to the left side, whereby to dump the car body to the right. In order to accomplish this, one of the bolsters 1 is provided with an upwardly curved slotted frame 12 having two racks 13 and guiding tracks 14, this frame, as herein shown, extending transversely of the car frame from one side to the other. The cylinder 9 when in operative position is supported on trunnion blocks 15 which rest in trunnion blocks carried by the bolster 1, at the ends of the curved frames, so that the cylinder is firmly supported at opposite sides.

To shift the cylinder 9 from one side to the other, there is provided a stub shaft 16 on which are mounted rollers 17 and gears 18, 19, the gear 18 meshing with the rack 13 and the rollers 17 rolling on frames 12 as the cylinder moves over from one side to the other. In order to revolve the gear 18, the gear 19 meshes with a gear 20 mounted on a short shaft 21, which can be turned by the hand crank 22 to roll the gear 18 over the rack 13 and thereby lift the cylinder from one side to the other, this movement not changing the position of the piston 10 for the reason that the rack 13 has as its center the center of the trunnion 6. Fastening means may be used if desired for locking the cylinder in the trunnion blocks, though ordinarily the weight of the parts will be sufficient to hold the cyl-

inder, as there is no moment tending to lift it. The cylinder is provided with pipes 26, 27 leading to opposite ends and will be connected by suitable pipes and controlling 5 valves with a source of fluid pressure, such as steam, air, or the like, in the well known manner, these parts not being shown herein as they do not form a part of this invention.

It is thought that the operation will be obvious from the foregoing description, it being understood that when it is desired to shift the cylinder from one side to the other the crank 22 will be operated to cause the gear 18 to ride on the rack 13 and lift the cylinder from 15 one side to the other. Suitable checking devices for checking the movement of the car body as it approaches the ends may be provided and it will of course be understood that the under frame will be provided with the 20 usual end couplings in order to permit a number of cars to be gathered into a train.

Modifications and changes will be made in the specific construction without departing from the scope of the invention.

Having thus described our invention, we declare that what we claim as new and desire to secure by Letters Patent, is:

1. The combination with a car body mounted to move laterally in either direction from a central position, of a motor for actuating the car body, and means whereby said motor can be swung vertically about the point of application of power from one side to the other to reverse the operation of the 35 car body.

2. The combination with a tilting and laterally movable car body moving in opposite directions from a central position, of a motor for actuating the car body, and means whereby said motor can be swung on the axis of tilting of the car body as a center from one side to the other to reverse the operation of the car body.

3. The combination with a car body mounted to move laterally in either direction from a central position, of a motor cylinder and piston for actuating the car body, the piston being connected with the car body to operate the same, and means for swinging 50 the motor and piston rod vertically about the connection of the piston rod and car body to reverse the operation of the car body.

4. The combination with a car body mounted to tilt and move laterally in either direction from a central upright position, of 55 a motor cylinder and movable piston for actuating the car body and connected therewith, the motor cylinder and piston being mounted to be swung on the axis of tilting of the car body as a center from one side of the 60 car frame to the other to reverse the operation of the car body, and supports carried by the car frame for supporting the motor cylinder in either position.

5. The combination with a car body 65 mounted to tilt and move laterally in either direction from a central upright position, of a motor cylinder and movable piston for actuating the car body, the motor cylinder with the piston being movable to a plurality 70 of positions to reverse the operation of the car body, and a track carried by the car frame for carrying the weight of the cylinder and piston while being moved from one position to the other.

6. The combination with a car body mounted to tilt and move laterally in either direction from a central upright position, of a motor cylinder having a movable piston for actuating the car body, the motor cylinder 80 with the piston being movable vertically about the axis of tilting from one side to the other to reverse the operation of the car body, and a curved track carried by the car frame for supporting the car body.

7. The combination with a car body mounted to tilt and move laterally in either direction from a central upright position, of a motor cylinder having a movable piston for actuating the car body, the motor cylinder 90 with the piston being movable vertically about the axis of tilting from one side to the other, to reverse the operation of the car body, and a rack and gear for moving the motor cylinder from one position to the 95 other.

In testimony whereof we affix our signatures, in presence of two witnesses.

MUNSON H. TREADWELL.
CARL P. ASTROM.
